UNITED STATES PATENT OFFICE.

LERoy V. CRAM, OF FLINT, MICHIGAN, ASSIGNOR TO GENERAL MOTORS CORPORATION, OF DETROIT, MICHIGAN, A CORPORATION OF DELAWARE.

OIL-PUMP SCREEN.

Application filed October 5, 1927. Serial No. 224,180.

My invention relates to lubricating systems for internal combustion and other engines of the type wherein oil is withdrawn from the crankcase of the engine by a suitable pump, and forced by the pump to various parts to be lubricated, or to various places where a supply of oil has to be maintained; an example of such a system, and a system wherein my invention is made use of, 10 being disclosed in the application for patent filed by Charles W. McKinley and myself upon May 19, 1927, Serial Number 192,712. My invention relates particularly to a strainer or filter designed for use in lubricating systems of the type just mentioned; the purpose thereof being to prevent, so far as possible, the entrance of impurities into the oil pump and their presence in the stream of oil forced thereby to the various 20 parts to be lubricated.

The drawing accompanying and forming a part of this specification illustrates the preferred form of my invention; although the same may be embodied in other forms, 25 and I regard my invention as embracing and including all such other forms as come within the scope of the concluding claims, wherein the particular features in which my invention consists are particularly pointed 30 out and claimed.

In the drawing:

Figure 1 is a view showing my invention as applied to the suction pipe of an oil pump of an engine lubricating system.

Figure 2 is a fragmentary view showing a detail of my invention.

Figure 3 is a view showing a blank cut from coarse and comparatively heavy woven wire screen material, and which when 40 properly shaped provides a protecting shield element of my improved strainer.

Figure 4 is a view showing a protecting shield formed from the blank shown in Figure 3, the view showing the shield in end elevation.

Figure 5 is a perspective view illustrating the features shown in plan in Figure 2.

Figure 6 is a view showing a section upon a transverse plane indicated by the line 6, 50 6, Figure 1, looking up.

Figure 7 is a fragmentary view showing a section upon a plane perpendicular to the sheet of the drawing and indicated by the line 7, 7, Figure 1, and upon a larger scale 55 than Figure 1.

Referring to the drawing, the reference numeral 9 designates, conventionally, the cylinder block of an internal combustion or other engine; 10 the oil pan to which oil returns by gravity from the various parts lubricated, and which normally contains a considerable quantity of oil; 11 an oil pump, one of the rotary variety, for example, as in the application for patent hereinbefore mentioned; 12 the suction pipe through which oil from the crank case enters the pump; and 13 the discharge pipe leading from the pump to the various parts and places to be supplied with oil.

The reference numeral 14 designates a disc-shaped screen supporting member which is made from sheet metal and which, while shown as slightly conical in form, does not differ materially from a flat and commonly circular disc. The middle part of this 70 supporting member is slotted by a suitable tool to provide a plurality of triangular lugs 15, which are bent out at right angles to the plane of the member 14, and extend laterally therefrom, said lugs being spaced 75 around a central opening in the screen support. A guide tube 16 is arranged in the opening, and the lugs are fastened to the tube as by welding, soldering or otherwise; the tube when assembled with the member 80 14 extending at right angles thereto. This tube will be slightly greater in diameter than the suction pipe 12 of the pump with which my device is to be used; so that the tube forms a guide for the strainer as a whole 85 and maintains it in substantially the relation to the suction tube illustrated in Figure 1. The strainer as a whole is held down against the bottom wall of the oil pan 10 by a spring 17 which surrounds the guide tube 16 and the suction pipe 12 with which the tube is 90 concentric.

The numeral 18 designates a filtering screen the mesh of which is sufficiently fine to prevent impurities of any appreciable size from passing therethrough and to the pump. It is made from a circular blank, not shown, which is given a substantially semispherical form by the use of suitable dies; and the free edge about the open upper end of the 100 formed screen is fastened to the screen support 14 along the periphery thereof. Preferably this fastening is accomplished by forming an outward extending flange at the upper end of the screen as it is shaped from 105 110

the blank, and turning the periphery of the screen support inward and onto the flange by the use of suitable dies, to thereby form a seam between the parts of substantially 5 the form shown in Figures 1 and 7. The upper end of the semispherical screen may, however, be secured to the periphery of the screen support 14 by soldering, or in any other suitable way.

10 The fine mesh screen 18 is made from such light screen stock or wire cloth that it is likely, if not protected, to be injured in handling the strainer, or during the manufacture thereof, and again even the slight 15 pressure of the spring 17 might collapse the screen as it holds it against the bottom wall of the oil pan. Therefore and in order to guard against the above mentioned and other 20 injuries I provide an external protecting shield for the screen, the same being much more resistant to forces tending to crush or otherwise injure the screen than the screen itself.

In the preferred form of my invention illustrated 25 the protecting shield is designated by the numeral 19; the same being in the form of a coarse mesh and comparatively heavy wire screen which overlies the more delicate screen 18 and prevents injury thereto. This shield is made from a blank cut 30 from screen stock of the proper mesh and size of wire, the blank being of approximately the shape shown in Figure 3. The blank is then given a form such that it will 35 fit quite closely over the screen 18, as by the use of suitable forming dies, the shield in its finished form being shown in end elevation 40 in Figure 4. Preferably the shield overlies the middle part only of the screen 18, as the protection thus afforded is quite sufficient, and a shield of the form shown 45 may be much more easily formed from the heavy screen material or wire cloth from which it is made than a shield truly semispherical in form, like the screen which it overlies and protects. The ends of the shield 19 are fastened to the screen supporting member 14 at opposite points in the periphery thereof as by flanging the ends and 50 enclosing flanges in the seam formed by bending the periphery of the member 14 inward and onto the flange of the screen 18, as best shown in Figure 7 of the drawing; although the ends of the shield may be fastened to the screen support by soldering, or 55 in any other suitable manner.

In view of the premises it will be appreciated that the fine mesh and comparatively frail screen 18 is protected by a much 60 stronger shield 19 which overlies the same, thereby preventing injury to the screen during the manufacture and handling thereof,

and thereafter when it is in use in the manner contemplated.

Having thus described and explained my 65 invention, I claim and desire to secure by Letters Patent:

1. A strainer comprising a disc-shaped screen support having a tubular guide extending therefrom, a fine mesh filtering screen semispherical in form, and the free edge of which is secured to said support along the periphery thereof; and a perforated protecting shield arranged outside said screen and secured to the periphery of said 70 disc-shaped screen support. 75

2. A strainer comprising a disc-shaped screen support, a fine mesh filtering screen semispherical in form, and the free edge of which is secured to said support along the 80 periphery thereof; and a protecting shield made from coarse mesh screen material arranged outside said fine mesh screen and secured to the periphery of said disc-shaped screen support. 85

3. A strainer comprising a disc-shaped screen support the periphery of which is turned inward and made to overlie the outer part of its body portion, a fine mesh filtering screen semispherical in form and the free edge of which is turned outward, and is held between the inturned periphery and the body portion of said screen support; and a protecting shield made from coarse mesh screen material arranged outside of and overlying 90 the middle part of said filtering screen, and the ends of which are also held between the inturned periphery and the body portion of 95 said screen support.

4. A strainer comprising a disc-shaped 100 screen support having a tubular guide extending therefrom, a fine mesh filtering screen semispherical in form, and the free edge of which is secured to said support along the periphery thereof; and a protecting shield made from coarse mesh screen material arranged outside of and overlying a 105 part only of the surface of said filtering screen, and the ends of which shield are secured to the periphery of said screen support 110 at opposite parts thereof. 115

5. In a strainer of the class described, a disc-shaped screen support made from sheet metal and having a plurality of triangular lugs cut free and bent so as to extend laterally therefrom, and which lugs are disposed about an opening in said support; and a tubular guide arranged in said opening and secured to said triangular lugs and extending at right angles to said screen support. 120

In testimony whereof I affix my signature.

LEROY V. CRAM.
